(57) **CLAIM**

The ornamental design for an accessory for planer attachment, as shown and described.

DESCRIPTION

FIG. 1 is a front perspective view of an accessory for a planer attachment.

FIG. 2 is a front view of the accessory shown in FIG. 1.

FIG. 3 is a rear view of the accessory shown in FIG. 1.

FIG. 4 is a first side view of the accessory shown in FIG. 1.

FIG. 5 is a second side view of the accessory shown in FIG. 1.

FIG. 6 is a top view of the accessory shown in FIG. 1; and, FIG. 7 is a bottom view of the accessory shown in FIG. 1. The dot dash dot broken lines immediately adjacent to the shaded areas represent bounds of the claimed design, while all other broken lines represent unclaimed portions of the accessory for planer attachment; the broken lines form no part of the claimed design.

1 Claim, 7 Drawing Sheets
